No. 799,186.

PATENTED SEPT. 12, 1905.

R. C. QUIN.

AIR BRAKE SYSTEM FOR STREET RAILWAYS.

APPLICATION FILED JAN. 24, 1905.

UNITED STATES PATENT OFFICE.

RICHARD C. QUIN, OF TORONTO, CANADA.

AIR-BRAKE SYSTEM FOR STREET-RAILWAYS.

No. 799,186.

Specification of Letters Patent.

Patented Sept. 12, 1905.

Application filed January 24, 1905. Serial No. 242,541.

To all whom it may concern:

Be it known that I, RICHARD C. QUIN, of the city of Toronto, in the Province of Ontario, Canada, have invented certain new and useful 5 Improvements in Air-Brake Systems for Street-Railways, of which the following is a specification.

The object of my invention is to devise means whereby an emergency application of 10 the air-brake of an electric car will simultaneously cut off the power, sand the track, trip a car-fender, and ring the bell.

A further object is to provide suitable means whereby each of these operations may be performed independently without affecting the 15 others.

With these objects in view my invention consists, essentially, of the constructions and arrangements hereinafter specifically described and then definitely claimed.

Figure 1 is a diagrammatical plan view of the improved apparatus. Fig. 2 is a sectional elevation of the sander. Fig. 3 is a sectional plan view of the sander-valve.

25 In the drawings like letters of reference indicate corresponding parts in the different figures.

Referring particularly to Fig. 1, A is the air-reservoir of the air-brake system. This 30 may belong either to a storage system or a system in which the air is pumped into the reservoir by means of pumps, electric or otherwise, carried by the car itself. A pipe C leads from the reservoir and is connected 35 with a motorman's valve B. This valve may be of any suitable four-way type. With this valve are connected the pipe E, communicating with the brake-cylinder F, the emergency-application pipe G, and the exhaust-pipe D.

40 The emergency-application pipe G is connected with the pipe E, and in this pipe is placed a check-valve *a*, which will permit of the passage of air through the pipe G into the pipe E, but will prevent air backing up from the 45 pipe E when air is admitted to the latter for ordinary stops. A pipe H connects the pipe G with the sanders I. Any construction of sander adapted to be operated by air-pressure will answer the purpose of the invention, 50 though I prefer to employ an air-driven wheel *b*, such as shown at the left hand in the drawings, to operate a rotary sander, such as shown in Fig. 3, which is substantially such as shown in United States Patent No. 704,210, dated 55 July 8, 1902. It will be seen that a rotatable

pan *c* is supported below the mouth of a suitable hopper *d*, the mouth of the hopper extending within the pan. A cone *c* is connected with the pan and extends up into the hopper. To the hopper is secured a plow *f*. The sand from the hopper enters within the pan, and as the latter is rotated the plow causes it to lift up and fall over the side of the pan. Thence it is directed to the track. It is evident that the movement of the air-driven wheel *b* will impart the necessary rotary motion to the sander. It will be noticed that the pipe C is also connected to the sander by means of the pipe J, in which is located the sander-valve K. This valve, as will be seen on reference to Fig. 3, has its rotary part *g* provided with a number of ports *h* of different sizes, which may be brought successively into connection with the outlet-port *i*. A large port *j* is provided, communicating with the 75 ports *h*, which may be brought into communication with the inlet-port *k*, while any one of the ports *h* is in communication with the outlet. Thus a greater or less quantity of air can be sent to the sanders, adapted to the speed at 80 which the car is running, so as to give a proportionate quantity of sand. By means of this sander-valve sand may be employed at any time without reference to the other parts of the mechanism. A check-valve *q* is placed in 85 the pipe H to prevent air backing up when the pipe J is open to the reservoir. The pipe C is also connected, by means of a pipe L, with a bell-ringing attachment M. This will comprise a wheel precisely similar to *b*, operating 90 a verge and escapement movement *l*, such as commonly employed in alarm-clocks. The passage of air to the bell-operating mechanism is controlled by a foot-operated valve N. A pipe O connects the bell-ringing attachment 95 either directly with the part G or indirectly through the pipe H connected with the sander, so that when air is passed through the pipe H to operate the sander it will also operate the bell. A check-valve *r* in the pipe H between 100 the connection with the pipe O and the valve B prevents air backing up when the pipe O is open, and a check-valve *s* in the pipe O between its connection with the pipe L and its connection with the pipe H prevents air from 105 the pipe O passing to the sander when the valve N is open. The pipe G is connected, by means of a pipe P, with cylinders Q and R. The cylinder Q is provided with a suitable piston and piston-rod *m*, the rod being adapt- 110

ed to contact with and move the electric switch *n*. This switch will control the passage of the electric current to the motors, so that when the switch is moved by the extension of the 5 piston-rod the power is cut off. A suitable spring will be provided within the cylinder to return the piston to its normal position. The cylinder *R* is arranged in precisely the same manner as the cylinder *Q*; but its piston-rod *o* is adapted to engage the pivoted latch *p*, which 10 supports the pivoted fender *S* in its normal position. This fender may be of any type which is tripped to its operative position either automatically or by the motorman and 15 that shown is merely for the purpose of illustrating the operation of my system. The latch *p* is shown engaged with a suitable catch. The piston *o* engaging the rear side of the latch is adapted to force the latter off 20 the catch and drop the fender.

From this description it will be seen that the motorman may by sending the air through the pipe *E* apply the brakes for service stops without interfering with either the fender, 25 the switch, the bell, or the sander, but that he may at the same time also ring his bell by foot or by hand independently operate the sanders, and it is of course evident that the switch or fender may be also manually operated, if desired. If, however, an emergency 30 stop is made, the air passes through the pipe *G* and thence through the pipe *E* to the brake-cylinders and at the same time passes to the sanders, the bell, the fender, and switch-operating means. Thus the one movement of 35 the motorman's valve will set the brakes, cut off the power, sand the track, ring the bell, and trip the fender.

I have also in this system avoided one of 40 the objections to the sander described in the United States patent already referred to—that is, that it required the motorman to turn a handle continuously while sand was being applied. With my present arrangements, either 45 during service stops or emergency stops, the sand is applied by the simple operation of a valve.

I am aware that it is not new to operate a sander simultaneously with the applying of 50 the air-brakes, that fenders have also been simultaneously tripped with the operation of the brakes, but I am not aware of any prior construction in which a special emergency air-pipe is provided, so that when air is admitted 55 to such pipe for the purpose of making an emergency stop sand is thrown onto the tracks or the fender is operated simultaneously therewith.

What I claim as my invention is—

60 1. In apparatus of the class described a brake-cylinder; air-operated sander-controlling means; and an air-operated fender-trip, in combination with a pipe supplying air to the brake-cylinder for service stops; a pipe 65 supplying air to the brake-cylinder for emer-

gency stops and communicating also with the sander-controlling means and the fender-trip; an air-supply pipe; and a valve adapted to place the air-supply pipe in communication with either of the aforesaid pipes, substantially as described. 70

2. In apparatus of the class described a brake-cylinder; air-operated sander-controlling means; an air-operated fender-trip; and an air-operated electric switch, in combination with a pipe supplying air to the brake-cylinder for service stops; a pipe supplying air to the brake-cylinder for emergency stops and communicating also with the sander-controlling means and the fender-trip and switch-operating means; an air-supply pipe; and a valve adapted to place the air-supply pipe in communication with either of the aforesaid pipes, substantially as described. 75 80

3. In apparatus of the class described a brake-cylinder; air-operated sander-controlling means; an air-operated fender-trip; an air-operated electric switch; and an air-operated bell, in combination with a pipe supplying air to the brake-cylinder for service stops; a pipe supplying air to the brake-cylinder for emergency stops and communicating also with the sander-controlling means, the fender-trip, the switch-operating means and the bell-operating means; an air-supply pipe; and a valve 90 adapted to place the air-supply pipe in communication with either of the aforesaid pipes, substantially as described. 95

4. In apparatus of the class described the combination of the motorman's valve *B*; the air-reservoir *A*; the pipe *C* communicating with the reservoir and the valve; the brake-cylinder *F*; the pipe *E* communicating with the valve and with the brake-cylinder; a pipe *G* for emergency stops communicating with the valve *B* and with the pipe *E*, substantially as described. 100 105

5. In apparatus of the class described the combination of the motorman's valve *B*; the air-reservoir *A*; the pipe *C* communicating with the reservoir and the valve; the brake-cylinder *F*; the pipe *E* communicating with the valve and with the brake-cylinder; a pipe *G* for emergency stops communicating with the valve *B* and with the pipe *E*; a pipe communicating with the pipe *G* to convey air to an air-operated mechanism; and a check-valve in the pipe *G* between its connection with the aforesaid pipe and its connection with the pipe *E*, substantially as described. 110 115 120

6. In apparatus of the class described the combination of the motorman's valve *B*; the air-reservoir *A*; the pipe *C* communicating with the reservoir and the valve; the brake-cylinder *F*; the pipe *E* communicating with the valve and with the brake-cylinder; a pipe *G* for emergency stops communicating with the valve *B* and with the pipe *E*; an air-operated sander; a pipe *H* communicating with the said sander and the pipe *G*; and a check-valve 125 130

in the pipe G between its connection with the aforesaid pipe and its connection with the pipe E, substantially as described.

7. In apparatus of the class described the combination of the motorman's valve B; the air-reservoir A; the pipe C communicating with the reservoir and the valve; the brake-cylinder F; the pipe E communicating with the valve and with the brake-cylinder; a pipe G for emergency stops communicating with the valve B and with the pipe E; an air-operated sander; a pipe H communicating with the said sander and the pipe G; a check-valve in the pipe G between its connection with the aforesaid pipe and its connection with the pipe E; a pipe J communicating with the pipe C and the pipe H; a manually-operated air-controlling valve in said pipe; and a check-valve in said pipe H between its connection with the pipe J and its connection with the pipe G, substantially as described.

8. In apparatus of the class described the combination of the motorman's valve B; the air-reservoir A; the pipe C communicating with the reservoir and the valve; the brake-cylinder F; the pipe E communicating with the valve and with the brake-cylinder; a pipe G for emergency stops communicating with the valve B and with the pipe E; an air-operated sander; a pipe H communicating with the said sander and the pipe G; a check-valve in the pipe G between its connection with the aforesaid pipe and its connection with the pipe E; a pipe J communicating with the pipe C and the pipe H; a manually-operated air-controlling valve in said pipe; a check-valve in said pipe H between its connection with the pipe J and its connection with the pipe G; an air-operated bell-ringing mechanism having direct communication with the air-reservoir and also a communication with the emergency air-pipe G; and a manually-operated valve adapted to control the direct communication, substantially as described.

45 9. In apparatus of the class described the combination of the motorman's valve B; the air-reservoir A; the pipe C communicating with the reservoir and the valve; the brake-cylinder F; the pipe E communicating with the valve and with the brake-cylinder; a pipe G for emergency stops communicating with the valve B and with the pipe E; an air-operated sander; a pipe H communicating with the said sander and the pipe G; a check-valve in the pipe G between its connection with the aforesaid pipe and its connection with the pipe E; a pipe J communicating with the pipe C and the pipe H; a manually-operated air-controlling valve in said pipe; a check-valve in said pipe H between its connection with the pipe J and its connection with the pipe G; an air-operated bell-ringing mechanism; a pipe L communicating with mechanism and the pipe C; a manually-operated valve N therein; 65 a pipe O communicating with the pipe L and

with the pipe H above the beforementioned check-valve therein; a second check-valve in the pipe H between its connection with the pipe O and its connection with the pipe G; and a check-valve in the pipe O, substantially as described.

10 10. In apparatus of the class described the combination of the motorman's valve B; the air-reservoir A; the pipe C communicating with the reservoir and the valve; the brake-cylinder F; the pipe E communicating with the valve and with the brake-cylinder; a pipe G for emergency stops communicating with the valve B and with the pipe E; an air-operated sander; a pipe H communicating with the said sander and the pipe G; a check-valve in the pipe G between its connection with the aforesaid pipe and its connection with the pipe E; a pipe J communicating with the pipe C and the pipe H; a manually-operated air-controlling valve in said pipe; a check-valve in said pipe H between its connection with the pipe J and its connection with the pipe G; an air-operated bell-ringing mechanism; a pipe L communicating with mechanism and the pipe C; a manually-operated valve N therein; a pipe O communicating with the pipe L and with the pipe H above the beforementioned check-valve therein; a second check-valve in the pipe H between its connection with the pipe O and its connection with the pipe G; air-operated fender-tripping means; and a pipe P communicating with the said means and with the pipe G, substantially as described.

100 11. In apparatus of the class described the combination of the motorman's valve B; the air-reservoir A; the pipe C communicating with the reservoir and the valve; the brake-cylinder F; the pipe E communicating with the valve and with the brake-cylinder; a pipe G for emergency stops communicating with the valve B and with the pipe E; an air-operated sander; a pipe H communicating with the said sander and the pipe G; a check-valve in the pipe G between its connection with the aforesaid pipe and its connection with the pipe E; a pipe J communicating with the pipe C and the pipe H; a manually-operated air-controlling valve in said pipe; a check-valve in said pipe H between its connection with the pipe J and its connection with the pipe G; an air-operated bell-ringing mechanism; a pipe L communicating with the mechanism and the pipe C; a manually-operated valve N therein; a pipe O communicating with the pipe L and with the pipe H above the beforementioned check-valve therein; a second check-valve in the pipe H between its connection with the pipe O and its connection with the pipe G; air-operated fender-tripping means; an air-operated electric switch; and a pipe P communicating with the said switch-operating means, the fender-tripping means, and the pipe G, substantially as described.

12. In apparatus of the class described the combination of an air-reservoir; an air-operated sander; a pipe between the reservoir and sander; a valve in said pipe comprising a casing with inlet and outlet ports and a rotary part having a series of ports therein of graduated sizes and opposite thereto a single large port communicating with each of the smaller ports and so shaped that when any one of the smaller ports is in communication with one of the ports in the casing the large port is in communication with the other port in the casing, substantially as described.

13. In apparatus of the class described the combination of an air-brake system; a rotary sander; an air-motor adapted to operate the sander; a pipe communicating with the air-brake system and the sander; and a valve controlling the air-supply through a pipe to the motor, substantially as described.

Toronto, January 19, 1905.

RICHARD C. QUIN.
